UNITED STATES PATENT OFFICE.

FRED I. RAYMOND, OF TWO BUTTES, COLORADO.

DEVICE FOR ENABLING AN AIRPLANE-MOTOR TO DEVELOP ITS FULL POWER AT HIGH ALTITUDES.

1,398,280.

Specification of Letters Patent. Patented Nov. 29, 1921.

Application filed June 5, 1918. Serial No. 238,405.

To all whom it may concern:

Be it known that I, FRED I. RAYMOND, a citizen of the United States, residing at Two Buttes, in the county of Baca and State of Colorado, have invented certain new and useful Improvements in Devices for Enabling an Airplane-Motor to Develop Its Full Power at High Altitudes, of which the following is a specification.

10 This invention relates to a device by means of which an airplane motor or other internal combustion motor will be enabled to develop its full power at high altitudes.

As an airship rises to higher altitudes it naturally comes in contact with air of an increasingly rarefied condition, the density of the air at high altitudes being quite small. For example, the pressure of the air at an altitude of 33,000 feet is approximately four 20 pounds per square inch absolute. Since internal combustion engines, which are universally used for the propulsion of airships, airplanes and the like, require for their successful operation a continuous supply of air 25 in order to produce the necessary compression in the cylinders, an efficient mixture of the fuel and the like, and the source of which air is that surrounding the airship it is obvious at the high altitudes where the 30 density of the air is quite small that unless means are provided to compensate for this rarefied condition of the air the efficiency of the internal combustion engine will be very materially decreased. Also these high altitudes are accompanied by low temperatures, thus setting up conditions under which it is very difficult for the aviator to operate, due to the intense cold. The aviator is further handicapped by the great difference 35 between the pressure of the air at the high altitudes and that at the surface of the earth, the extremely low pressures having a very marked effect upon the beating of the heart, the action of the respiratory organs 40 and the like.

By the present invention the above difficulties are overcome and in accomplishing this result I propose to provide a device by means of which air may be continuously 45 supplied to the cylinders of the internal combustion engine at a constant predetermined pressure (preferably atmospheric pressure, that is 14.7 pounds per square inch absolute), and to provide a compartment 50 for the aviator within which the air may be kept not only at a constant predetermined

pressure, but also may be maintained at a suitable working temperature, thus greatly increasing the comfort and safety of the aviator and the efficiency of the engine, the 60 result of which will be to render possible attaining much greater altitudes than heretofore possible.

Among the objects of this invention is to provide such an arrangement that a continuous supply of air may be furnished at a constant predetermined pressure (preferably atmospheric pressure) to the cylinders of an internal combustion engine regardless of the elevation with relation to sea level that the 65 same may be operated; further to enable an airplane to develop its full power at high altitudes by providing at all times air to the carburetor and cylinders at atmospheric pressure; to enable an airplane to attain 70 greater altitudes than heretofore possible; to enable an airplane to travel faster at high altitudes; to enable an airplane to travel farther at high altitudes with a given supply of fuel, in other words to increase its 75 range of flight; further to provide for the aviator a working temperature and atmospheric pressure at all times, thus facilitating his actions and relieving him of undue strain; to eliminate all causes of motor 80 trouble accompanying flights at high altitudes; further to provide means for regulating at will the temperature of the air in the aviator compartment while the pressure remains constant; further to provide a novel 85 form of means for maintaining the air for both the engine cylinders and the aviator's compartment at atmospheric pressure; and such further objects, advantages and capabilities as will later more fully appear. 90 95

My invention further resides in the combination, construction and arrangement of parts illustrated in the accompanying drawings and while I have shown therein a preferred embodiment of my invention, I desire the same to be understood as illustrated only and not as limiting the scope of my invention.

In the drawings:

Figure 1 is an elevation of an airplane, 105 partly broken away to show the interior parts, and embodying my invention.

Fig. 2 is a vertical transverse sectional view taken on the line 2-2 of Fig. 3.

Fig. 3 is a horizontal section taken on the 110 line 3-3 of Fig. 4.

Fig. 4 is a vertical longitudinal frag-

mentary sectional view taken through the forward part of the airplane and showing the arrangement of the motor, air compressor, aneroids and the aviator's compartment.

- 5 Referring to the drawings, 1 designates generally an airplane embodying my invention. In the forward portion of the airplane is located a standard airplane motor 10 2 from the side of which extends the carbureter manifold 3 in which is located the carbureter 4. Connecting the carbureter with the air compressor 5 is the passageway 6, which as shown in Fig. 4 preferably extends 15 forwardly along the floor of the airplane and thence upwardly and rearwardly to the carbureter; however, it is apparent that any other desired arrangement of this passageway may be employed.
- 20 Located back of the engine compartment is the aviator's compartment 7, the opening 8 of which is preferably closed by glass 9; it being obvious that suitable windows may be located around the compartment 7 in such 25 positions as to give the aviator a maximum outlook.

The air compressor 5 is of the positive blower or rotary compressor type as is clearly shown in Fig. 2 and comprises the 30 usual intermeshing blades 10 and 11, which are driven by the gear wheels 12 and 13. The blade 10 is mounted directly upon the engine shaft and the blade 11 geared thereto as just stated through the medium of the 35 gears 12 and 13, as a result of which both of these blades will rotate uniformly. At the air compressor end of the passageway 6 is the upwardly extending pipe 14, upon the upper end of which is slidably mounted the 40 hood 15, the upper end of which is formed so that when the hood is in its upper most position its upper open end will register with the exhaust outlet 16 of the air compressor. This hood is arranged so that it 45 may be raised or lowered at will by the aviator for a purpose to be later more fully explained.

Connecting the air compressor with the exterior of the airplane is the inlet passage 50 17 which has an opening at its outer end, preferably faced in the direction in which the airplane is traveling to facilitate the entry of the air thereinto. Located within suitable bearings 18 and 19 in the inlet 55 17 is the stem or vertical shaft 20, upon the lower end of which and fitting within the air inlet 17 is the butterfly valve 21. Upon the upper end of the shaft 20 are formed the oppositely extending arms 22, to the outer 60 ends of which are secured the rods or extensions 23 and 24 of the aneroids 25 and 26 respectively. These aneroids as is clearly seen in Fig. 2 are located within the aviator's compartment above the air compressor and 65 on opposite sides of the shaft 20. These

aneroids are supported upon any suitable frame and are provided with the usual means for regulating them.

The capacity of the air compressor is approximately from two to three times the displacement of the engine cylinders, and as stated above is driven by direct connection to the engine crank shaft.

The operation of my improved device is as follows: At sea level the compressor will 70 pump more air than the engine will displace, thus increasing the pressure of the air in the aviator's compartment 7, it being here pointed out that there is sufficient clearance left between the sliding hood 15 and the adjacent parts of the exhaust outlet 16 to permit leakage of air from the compressor to the compartment 7, whereby to maintain the compartment 7 at the same air pressure as the air being delivered from the air compressor. This increase of pressure in the compartment 7 will cause the aneroids 25, 26 to contract as a result of which the extension 23, 24 will operate upon the arms 22 in such manner as to rotate the valve 21 in a closing 80 direction. This closing, or partial closing as the case may be, of the valve 21 causes the compressor 5 to work under a partial vacuum which will in turn cause the pressure of the air being delivered through the outlet 16, 90 and consequently the pressure of the air in the compartment 7 to fall until it is the desired amount, approximately 14.7 pounds per square inch absolute, or in other words atmospheric pressure. This pressure will be 100 maintained by the action of the aneroids when properly adjusted. As the altitude increases the density of the air and its corresponding pressure decreases, the result of which will be to cause a drop of pressure in 105 the air being delivered from the compressor and consequently a drop of pressure of the air in the compartment 7. As a result of this drop of pressure, the aneroids will then expand and by an operation reverse to that described above will open the throttle valve or butterfly valve 21 and permit more air to enter the compressor 5, thus increasing the pressure of the air delivered from the compressor until the pressure of the air in the 115 compartment 7 and in the passageway 6 is again brought up to atmospheric pressure. Thus if the compressor 5 has twice the displacement of the engine pistons it will maintain the pressure in the passageway 6, and 120 in the compartment 7 at atmospheric pressure until an altitude of 20,000 feet has been reached, thus enabling the motor at this altitude to develop its full power, as a result of its being continuously supplied with air at 125 atmospheric pressure from the passageway 6, which air passing through the carbureter 4 is sufficiently enriched to supply explosive power to the cylinders in the usual manner. At 30,000 feet the compressor would have to 130

have three times the displacement of the engine pistons.

- As this rarefied air which at an altitude of say 33,000 feet would have a pressure of 5 approximately four pounds per square inch absolute is compressed, its temperature is of necessity increased, and by suitable manipulation of the sliding hood 15 a greater or less volume of this heated air may be permitted 10 to pass out into the compartment 7, whereby to establish a working temperature therein for the aviator. Should the temperature in this compartment rise too high for the aviator's comfort the volume of heated 15 air passing thereinto from the compressor may be cut down by raising the sliding hood 15, so as to decrease the amount thereof. If desired and found necessary the sliding hood 15 may be completely closed, that is placed 20 with its upper end in alinement of the exhaust outlet opening 16, at which time atmospheric pressure would be maintained in compartment 7 by leakage of air by these parts without carrying a great volume of 25 the heated air into the compartment, thus furnishing a means by which the temperature in the aviator's compartment can be regulated within certain limits. By this arrangement the aviator is enabled not only 30 to work in air at atmospheric pressure, but also to, at the same time, operate under a working temperature, thus relieving him from the sufferings of intense cold and undue strain.
- As is obvious since air is being delivered 35 to the internal combustion engine at atmospheric pressure the efficiency of this engine will be very greatly increased, thus making possible the attainment of considerably 40 higher altitudes, and while traveling at such higher altitudes to travel at a .7 greater speed at an altitude of 33,000 feet with the same power. Also it would enable the airplane to travel .7 farther with a given supply 45 of fuel, that is it would give it a range of flight .7 greater.
- The air delivered through the compressor exhaust, and which at high altitudes would be at too great a temperature for the comfort 50 of the aviator, were it not for the sliding hood, passes through the exhaust outlet at approximately the same rate at which the engine uses it, and the hood 15 simply aids its immediate passage into the channel leading 55 to the carbureter, however, the slight excess of air over that being required by the cylinders will be sufficient to make possible the regulation of the temperature within the compartment 7 by means of operation of the 60 sliding hood 15. The purpose of leading the passageway 6 to a point in advance of the carbureter before directing it thereto is to, if desired, make possible a greater or less cooling of the heated air coming from the 65 compressor 5.

While I have described my invention in connection with an airplane motor it is obvious that it is capable of use in other instances such for example as with an automobile engine when traveling in localities of 70 high altitude, and in any other instance where the pressure surrounding an internal combustion motor is different than atmospheric pressure at sea level. It may also be used with two cycle engines to effect a more 75 complete scavenging of the burned gases.

Having now described my invention.

I claim:

1. In apparatus of the class described, an internal combustion engine having a carbureter manifold and a carbureter connected thereto, an air compressor having its exhaust in communication with said carbureter, an inlet connecting said compressor with the outside air, and means in connection with 80 said compressor to maintain the air passing through said exhaust into said carbureter at substantially normal atmospheric pressure regardless of the pressure of the exterior air, said means comprising a valve in said inlet 85 whereby air may be fed at a variable regulable rate to the carbureter and means for controlling said valve, said last named means being entirely disassociated with the compressor exhaust. 90

2. In an airship, in combination, an internal combustion engine having a carbureter manifold, and a carbureter connected thereto, an air compressor having an exhaust outlet in communication with said carbureter, an air inlet connecting said compressor with the outside air, an air chamber in communication with said carbureter, and means in said chamber for automatically 100 controlling said air inlet to cause it to supply 105 air at varying regulable rates to the compressor, whereby to cause the air to be delivered at substantially atmospheric pressure to said manifold regardless of the altitude of flight of said airship, said controlling means being entirely disassociated with the compressor exhaust and the carbureter. 110

3. In an airship an internal combustion engine, an aviator's compartment, an air compressor driven by said engine, an exhaust outlet from said compressor to the engine cylinders, an inlet passage connecting said compressor with the outside air, a valve in said inlet, and means located in said compartment for automatically controlling said 115 valve whereby to maintain the air delivered from said compressor to said engine cylinders at substantially atmospheric pressure regardless of the altitude of flight. 120

4. In an airship an internal combustion 125 engine, an aviator's compartment, an air compressor driven by said engine, an exhaust outlet connection from said compressor to the engine cylinders, an inlet passage connecting the compressor with the outside air; 130

- a valve in said inlet passage, an air communication between said compressor and said compartment, and means in said compartment for automatically controlling said 5 valve to increase or decrease the volume of air admitted to said compressor whereby to maintain the air delivered to the said cylinders and to said compartment at substantially atmospheric pressure regardless of the 10 altitude of flight.
5. In an airship, an aviator's compartment, an internal combustion engine, an air compressor driven by said engine and located in said compartment, an exhaust outlet 15 on said compressor, a passageway leading to the engine cylinders, a sliding hood connecting said passageway and said exhaust outlet whereby to cause as desired a greater or less interchange of air from said exhaust outlet 20 into and from said aviator's compartment, an inlet passageway connecting said compressor with the outside air, a valve in said passageway, and means in said compartment and connected with said valve to automatically 25 regulate said valve to maintain at a predetermined pressure the air being delivered to said engine cylinders and said compartment.
6. In an airship, an aviator's compartment, an internal combustion engine, an air compressor driven by said engine and located in said compartment, an exhaust outlet on said compressor, a passageway leading to the engine cylinders, a carbureter in 30 said passageway; a sliding hood connecting said passageway and said exhaust outlet whereby to cause as desired a greater or less interchange of air from said exhaust outlet into and from said aviator's compartment, 35 an inlet passageway connecting said compressor with the outside air, a valve in said passageway, and means in said compartment and connected with said valve to automatically regulate said valve to maintain at 40 a predetermined pressure the air being delivered to said engine cylinders and said compartment, said means comprising a pair of aneroids operatively connected to produce a closing movement or opening movement 45 of said valve as the pressure in said compartment becomes respectively greater than or less than said predetermined pressure.
7. In apparatus of the class described having a cockpit, an internal combustion engine adapted to work at various positions with 50
- relation to sea level, an air inlet passageway leading to the engine cylinders, and means for supplying air to said passageway at a substantially constant predetermined pressure regardless of the elevation of said engine with relation to sea level, said means comprising a compressor, an air inlet passageway leading thereto, a regulable valve located in the last named air inlet passageway, and expansion means located in the cockpit and adapted to automatically operate the valve. 60
8. In an airship, an internal combustion engine, an air compressor, a passageway connecting said compressor with the engine cylinders, aneroid means to control the admission of air to said compressor to maintain the air delivered by it to said cylinders at a substantially constant predetermined pressure regardless of the altitude of said airship, and an aviator's compartment containing the air compressor and the aneroid means. 70
9. In an airship, an aviator's compartment, an internal combustion engine, an air compressor, a passageway connecting said compressor with the engine cylinders and with said compartment, and aneroid means to control the admission of air to said compressor to maintain the air delivered by it to said cylinders and the pressure in said compartment at a substantially constant predetermined pressure regardless of the altitude of the airship. 80
10. In an airship an aviator's compartment, an internal combustion engine, an air compressor, a passageway connecting said compressor with the engine cylinders and with said compartment, and aneroid means to control said compressor to maintain the air delivered by it to said cylinders and the pressure in said compartment at a substantially constant predetermined pressure regardless of the altitude of the airship, and adjustable means to regulate the volume of compressed air entering the compartment whereby to maintain a working temperature therein. 90
- In witness whereof, I hereunto subscribe my name to this specification in the presence of two witnesses: 105
